DESIGN FOR A LETTER OPENER

John J. Calichio, Forest Hills, N. Y.

Application June 29, 1946, Serial No. 131,176

Term of patent 14 years

(Cl. D74—1)

To all whom it may concern:

Be it known that I, John J. Calichio, a citizen of the United States of America, residing at Forest Hills, in the county of Queens and State of New York, have invented a new, original, and ornamental Design for a Letter Opener, of which the following is a specification, reference being had to the accompanying drawing, forming part thereof, wherein—

Figure 1 is a plan view of the letter opener embodying my new design, the top and bottom of the letter opener being identical.

Fig. 2 is a side elevational view of the letter opener shown in Fig. 1.

Fig. 3 is a sectional view taken along the plane of the line 3—3 of Fig. 1.

Fig. 4 is a sectional view taken along the plane of the line 4—4 of Fig. 1.

Fig. 5 is a sectional view taken along the plane of the line 5—5 of Fig. 1.

I claim:

The ornamental design for a letter opener, as shown and described.

JOHN J. CALICHIO.
